[57] CLAIM

The ornamental design for a finger ring setting, substantially as shown and described.

DESCRIPTION

FIG. 1 is a perspective view taken from the front, top and left side of a finger ring setting showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof; and

FIG. 7 is a cross sectional view taken along line 7—7 of FIG. 3.
